LATCH FOR PISTON RODS

Marion A. Garrison, South Pasadena, Calif., assignor to Kay-Brunner Steel Products, Inc., Los Angeles, Calif., a corporation of Delaware

Application November 24, 1950, Serial No. 197,341

8 Claims. (Cl. 121—40)

1

This invention relates to power operated earth moving equipment and is particularly directed to a novel form of latch construction for relieving a piston rod of a gravity load imposed by an earth-engaging tool while the tool is held in an inoperative raised position.

Gravity actuated earth-engaging tools are commonly employed on earth moving equipment. Such tools are lowered into operative position by gravity and are raised to an inoperative position by means of hydraulic cylinder assemblies. Unless some form of mechanical latch is provided for securing the tool in its inoperative raised position the weight of the tool imposes a back pressure on the hydraulic fluid supplied to the piston of the hydraulic cylinder assembly. The seal rings on the piston are therefore required to be continuously active in order that the pressure of the hydraulic fluid shall maintain the ground-engaging tool in its inoperative raised position.

In accordance with my invention I provide an automatic latch which acts to hold the ground-engaging tool in its inoperative raised position without imposing any back pressure on the hydraulic system and without requiring the hydraulic system to maintain the tool in elevated position. The construction of the latch is such that it is automatically released when pressure is applied to move the piston in a direction to lower the tool.

I have chosen to illustrate my invention as applied to a self-powered mobile loader device, but this environment is by way of illustration only, and it is to be understood that the automatic latch device is useful with apparatus of other types.

A feature of my invention is that the latch may be constructed so that the piston rod is latched against movement in either one of its directions of movement.

Other features and objects and advantages of this invention will appear hereinafter.

In the drawings:

Figure 1 is a perspective view partly broken away showing a mobile loader device having a gravity actuated scarifier, and showing a preferred embodiment of my invention interposed between the hydraulic cylinder assembly and the scarifier tool.

Figure 2 is a side elevation partly broken away and partly in section showing details of a preferred form of my invention in connection with the power cylinder assembly.

Figure 3 is a view similar to Figure 2 showing

2

the position of the parts shortly after the initial extending movement of the piston rod.

Figure 4 is an end elevation partly broken away of the device shown in Figure 3.

Figure 5 shows a modified form of my invention for automatically latching the piston rod in its extended position.

Referring to the drawings, the power cylinder assembly generally designated 10 may be mounted on a mobile device 11 having a ground-engaging gravity actuated tool 12 pivotally mounted on one end thereof. Pivot pins 13 may be provided for connecting the parallel arms 14 of the tool to the frame of the mobile device 11. As shown in the drawings the ground-engaging tool 12 takes the form of a scarifier having a weighted bar 15 extending transversely of the vehicle 11 and having a plurality of downwardly extending teeth 16 spaced thereon at intervals. A lug 17 may be welded or otherwise secured to one of the arms 14. A pair of straps 18 form a continuation of the lug 17 and are secured thereto by welding. The free ends of the straps are separated to form a yoke 19.

As shown in Figure 2, the yoke 19 is pivotally connected by means of pin 20 to the forwardly projecting ear 21 provided on the sleeve 22. The ear 21 is joined to the sleeve 22 by means of welding 23. The sleeve 22 is provided with a central axially extending bore 24 which is terminated at one end by the ear 21 and which is terminated at the other end by the annular shoulder 25. A smaller bore 26 extends axially through the one end of the sleeve 22 and communicates with the bore 24.

The power cylinder assembly 10 includes a cylindrical shell 27 positioned between spaced heads 28 and 29. The shell 27 and heads 28 and 29 are maintained in assembled relationship by means of the tie rods 30. The piston 31 is mounted to reciprocate within the shell 27, and this piston is secured to the piston rod 32 by any convenient means such as, for example, by the threaded nut 33. The piston rod 32 extends axially of the shell 27 and projects through the head 27 and through the stuffing box gland 34. The projecting end of the piston rod 32 is slidably received within the sleeve bore 26. An enlargement 35 may be formed integrally on the projecting end of the piston rod or may be formed as a separate ring welded or otherwise secured in place. This enlargement is received within the sleeve bore 24. One side of the enlargement 35 is provided with a radial shoulder 36 adapted to engage the shoulder 25. The other side of

3

the enlargement is tapered to provide a frusto-conical surface 37.

A plurality of latching pins 38 are provided for releasably securing the sleeve 22 with respect to the stationary body 39. The body 39 is fixed with respect to the cylindrical shell 27 and may conveniently be carried on extensions of the tie rods 30. Nuts 40 are provided on the tie rods 30 for maintaining the body 39 in position. Radially extending guide bores 41 are provided in the body 39, and the latching pins 38 are slidably mounted for radial movement in these bores 41. Compression springs 42 are provided in each of the guide bores for moving the latching pins 38 radially inwardly. Cover plates 43 serve to close the open ends of the radial bores 41 and also to engage the outer end of the compression springs 42. The cover plates 43 are secured in position by means of suitable attachment elements 44 which are threaded into the body 39.

The inner ends 45 of the latching pins 38 are bevelled for engagement with the frusto-conical surface 37 on the enlargement 35. A cylindrical portion 46 on these latching pins each extends through an aperture 47 provided on the sleeve 22. When the latching pins 38 project through the apertures 47 the sleeve 22 is effectively latched against movement with respect to the stationary body 39. When the latching pins 38 are retracted (as described below) against the action of the springs 42 the sleeve 22 is free to travel with the piston rod 32.

In the operation of that form of my invention shown in Figures 1-4, the latching pins 38 are normally in position as shown in Figure 2 so that the sleeve 22 is maintained in latching position. The ground-engaging scarifier tool 12 is thus latched in its inoperative raised position as shown in Figure 1 since the weight of the tool is transmitted through the parts 17, 18, 20 and 21 to the sleeve 22. When the operator desires to lower the scarifier 12 he actuates a valve (not shown) which applies hydraulic pressure through the fitting 48 to cause the piston 31 to move to the right as shown in Figure 2. The tapered surface 37 on the piston enlargement 35 then acts on the bevelled surfaces 45 of the latching pins 38 to cause them to move radially outwardly against the action of the springs 42. As soon as the cylindrical portion 46 of the pins 38 is retracted out of the apertures 47 the weight of the scarifier 12 acting about the pivots 13 applies a force to the ears 21 and sleeve 22, causing the sleeve to move to the right. The action of gravity in lowering the scarifier 12 may be supplemented by continuing to apply hydraulic pressure through the fitting 48. In this case the extreme forward end 50 of the piston rod 32 engages the radial surface 51 on the ear 21 so that a positive force is applied to move the ear 21 toward the right as viewed in Figure 2.

When it is desired to retract the scarifier 12 to its inoperative raised position, the operator actuates the control valve (not shown) to apply hydraulic pressure through the fitting 52. This applies hydraulic pressure on the right side of the piston 31 as viewed in Figure 2 and causes it to move to the left. This brings shoulders 36 and 25 into contact and brings the sleeve 22 into the central opening 53 within the body 39. The sleeve 22 is provided with a bevelled portion 54 which engages the bevelled ends 45 on the latching pins 38 and retracts them against the action of the compression springs 42. Continued movement of the piston 32 toward the

left as viewed in Figure 2 brings the latching pins 38 into alignment with the apertures 47 provided in the sleeve 22. The springs 42 then move the latching pins 38 into latching position as shown in Figure 2.

It is recognized that instead of hydraulic pressure the power cylinder assembly 10 may be operated by air pressure or by vacuum pressure. The power cylinder assembly 10 is pivotally mounted on the frame of the vehicle 11 by means of a pivot pin 59 so that the entire assembly may oscillate through a small angle about this pin when the piston rod is extended and retracted.

In the modified form of my invention shown in Figure 5 the sleeve is latched in its fully extended position instead of in its fully retracted position. In Figure 5 the body 39a is carried on the tie rod extensions 30a and held in place by means of nuts 40a in a manner similar to that described above. However, the extensions 30a are considerably longer than the tie rod extensions 30 by the amount of the stroke of the piston rod 32a. The piston rod 32a is provided with an enlargement 35a. This enlargement has a frusto-conical surface 37a which is engaged by the bevelled ends 45a on the latching pins 38a. The sleeve 22a extends through a central opening in the body 39a and carries the lug 21a which is connected by means of the pin 20a to the yoke 19a. When the piston rod 32a is fully extended as shown in Figure 5 the compression springs 42a move the latching pins 38a into the apertures 47a provided in the sleeve 22a. The sleeve 22a is thus latched against movement with respect to the stationary body 39a.

When the piston rod 32a is retracted toward the left as viewed in Figure 5 the frusto-conical surface 37a engages the bevelled ends 45a of the latching pins 38a and thereby moves the latching pins radially outwardly against the action of the compression springs 42a. When the cylindrical portion of the latching pins has passed out of the apertures 47a the sleeve 22a is free to move to the left as viewed in Figure 5. The force of the pressure fluid admitted through fitting 52 moves the piston rod 32a to the left, and this force may be applied to bring the shoulder 50a on the enlargement 35a against the surface 51a on the plate 60. This plate 60 is bored for sliding reception of the piston rod 32a and is secured to the sleeve 22 by means of welding 61.

When the piston 32a is caused to move to the right by pressure fluid the end surface 36a on the enlargement 35a engages the end surface 25a on the sleeve 22a to move it to the right. When the slanting surface 54a on the sleeve 22a engages the bevelled surface 45a on the latching pins 38a, the pins are moved radially outward against the action of the springs 42a. When the apertures 47a register with the pins 38a the latter move radially inwardly under the action of the springs 42a to latch the sleeve 22a with respect to the stationary body 39a.

Having fully described my invention, it is to be understood that I do not wish to be limited to the details herein set forth, but my invention is of the full scope of the appended claims.

I claim:

1. A releasable latch for a power cylinder assembly comprising in combination: a cylindrical shell, heads at opposite ends of the shell, tie rods connecting the heads to prevent disassembly of the heads and shell, the tie rods each having extending portions at one end, a body secured to the extending portions of the tie rods adjacent

one of the heads, the body having a central opening, a sleeve mounted for movement within the opening, a piston rod, a piston on the rod reciprocable within the shell, an enlargement on the piston rod at the extending end thereof, the sleeve having a central bore to receive the enlargement in telescopic relation, the sleeve having an aperture communicating with said bore, a latching element movably mounted on the body extending into said aperture to latch the sleeve against relative axial movement with respect to said body, and cooperating parts on the enlargement and latching element whereby axial movement of the enlargement within the sleeve bore away from said heads serves to move the latching element out of said aperture.

2. A releasable latch for a power cylinder assembly comprising in combination: a cylindrical shell, heads at opposite ends of the shell, tie rods connecting the heads to prevent disassembly of the heads and shell, the tie rods each having extending portions at one end, a body secured to the extending portions of the tie rods remote from both of said heads, the body having a central opening, a sleeve mounted for movement within the opening, a piston rod, a piston on the rod reciprocable within the shell, an enlargement on the piston rod at the extending end thereof, the sleeve having a central bore to receive the enlargement in telescopic relation, the sleeve having an aperture communicating with said bore, a latching element movably mounted on the body extending into said aperture to latch the sleeve against relative axial movement with respect to said body, and cooperating parts on the enlargement and latching element whereby axial movement of the enlargement within the sleeve bore toward said heads serves to move the latching element out of said aperture.

3. A releasable latch for a power cylinder assembly, comprising in combination: a cylindrical shell, heads at opposite ends of said shell, mounting rods extending from one end of said shell, a body secured to said mounting rods and axially adjustable thereon, the body having a central opening coaxial with said cylindrical shell, a sleeve mounted for movement within the opening, a piston rod, a piston on the rod reciprocable within the shell, an enlargement on the piston rod at the extended end thereof, the sleeve having a central bore to receive the enlargement in telescopic relation, the sleeve having an aperture communicating with said bore, a latching element movably mounted on the body extending into said aperture to latch the sleeve against relative axial movement with respect to said body, and cooperating parts on the enlargement and latching element whereby axial movement of the enlargement within the sleeve bore in one direc-

tion serves to move the latching element out of said aperture.

4. A releasable latch for a power cylinder assembly, comprising in combination: a cylindrical shell, heads at opposite ends of said shell, mounting rods extending from one end of said shell, a body secured to said mounting rods and axially adjustable thereon, the body having a central opening in coaxial relation with said cylindrical shell, a movable sleeve adapted to be secured within the central opening in the body, the sleeve having a central bore, a piston for said shell, a piston rod extending therefrom and having an enlargement at its extended end, the enlargement being secured within said bore of the sleeve, cooperating parts on the enlargement and sleeve permitting limited relative axial movement between the piston rod and the sleeve, the sleeve having an aperture communicating with said bore, a latching pin radially slidable on the body extending into said aperture to latch the sleeve against relative axial movement with respect to said body, a spring acting to move the latching pin into the aperture, and cooperating parts on the enlargement and latching pin whereby axial movement of the enlargement within the sleeve bore serves to move the latching pin out of said aperture against the action of the spring.

5. A combination as set forth in claim 3, wherein: said body is mounted adjacent said shell and said piston rod is latched when in its retracted position relative to said shell.

6. A combination as set forth in claim 3, wherein: said body is mounted in spaced relation to said shell and said piston rod is latched when in its extended position relative to said shell.

7. A combination as set forth in claim 4, wherein: said body is mounted adjacent said shell and said piston rod is latched when in its retracted portion relative to said shell.

8. A combination as set forth in claim 4, wherein: said body is mounted in spaced relation to said shell and said piston rod is latched when in its extended position relative to said shell.
